UNITED STATES PATENT OFFICE.

JOSEPH McCARTHY, OF FRANKLIN, OHIO.

VALVE.

1,172,895.

Specification of Letters Patent. Patented Feb. 22, 1916.

Application filed January 2, 1915. Serial No. 73.

To all whom it may concern:

Be it known that I, JOSEPH McCARTHY, a citizen of the United States, residing at Franklin, in the county of Warren and State of Ohio, have invented certain new and useful Improvements in Valves, of which the following is a specification, reference being had therein to the accompanying drawing.

10 This invention relates to valves such as are commonly used to cut off the flow of water to a tank when the tank has been filled to the desired level.

15 The object of the invention is to provide such a valve that can be easily kept in working condition.

20 To this end it is a further object of the invention to so construct the valve that it will be automatically cleaned, thereby preventing the corrosion or accumulation of matter on the valve to an extent that would interfere with the proper operation of the valve; and further to so construct the valve and the valve actuating device that the valve 25 member may be removed without disconnecting any part of the valve body or imparting movement to any part of the valve other than the movable valve member.

It is also an object of the invention to 30 provide means for automatically locking the valve against displacement during the filling operation.

In the accompanying drawings, Figure 1 is a side elevation, partly in section, of a 35 valve embodying my invention; and Fig. 2 is a top, plan view, partly in section, of such a valve.

40 In these drawings I have illustrated one embodiment of my invention and have shown the same as comprising a valve casing 1 having in its lower portion a chamber 2 which is provided with an inlet 3 and an outlet 4, this latter being preferably in the form of a spout to discharge into the tank 45 in the usual manner. The inlet is formed by a bushing 5 screwed into the lower portion of the casing and having a reduced upper portion 6 forming a valve seat. The inlet pipe 7 is screwed into the bushing 5. 50 The valve casing 1 is provided above and in alinement with the valve seat 6 with a guide opening 8 in which is slidably mounted a valve member 9 adapted to be moved into and out of engagement with the valve 55 seat 6. In the present form of the device

the guide opening 8 is formed in two parts, the upper portion of the opening, which is shown at 10, being spaced away from the lower portion thereof by means of a chamber 11. It will be noticed that this arrangement is brought about by providing the casing 1 with a central partition 12 arranged substantially midway between its ends and providing the partition and the top wall of the casing with openings 8 and 10, respectively. The valve member 9 is, as stated, slidably mounted in these guide openings for movement into and out of engagement with the valve seat and it comprises a body portion having two enlargements 13 and 14 fitting, respectively, in the openings 8 and 10 and serving to guide the valve in its movement. These enlarged portions of the valve are of such a length and are so arranged with reference to their respective 75 openings that the corresponding edges of the valve and of the openings will pass upon each complete movement of the valve, that is, the lower edges of the enlargement will pass into the respective openings as the valve moves upward and the upper edges of the enlargements will pass into the respective openings when the valve moves downward. This construction of the valve member produces a cleaning action in that the 80 passing edges serve to prevent any accumulation of matter or corrosion which would interfere with the operation of the valve. The chamber 11 is provided with openings or ports 15 to permit of the escape of the 85 fluid which seeps past the lower enlargement 13 of the valve, thus allowing this seepage to pass into the tank and preventing the water accumulating in the chamber 90 11 and offering resistance to the movement 95 of the valve member; as would be the case in the absence of the ports 15.

The actuating device for the valve member 9 is preferably in the form of an arm arranged above the casing 1 and movable 100 toward and away therefrom. This arm is arranged out of alinement with the guide opening 10 and the valve is connected thereto by means of interlocking parts carried by the arm and the valve, respectively. Thus, 105 the valve can be readily removed from its guide opening by merely disconnecting the interlocking devices, without disconnecting any other part of the valve mechanism. The valve actuating arm is here shown at 16 and 110

is pivotally mounted on a bracket 17 carried by the casing 1. That portion of the arm adjacent to the end of the valve casing is provided with an offset portion which is here shown as an annular enlargement 18 of a diameter greater than the diameter of the enlarged portions of the valve and the space within this annular portion of the arm is in alinement with the guide opening and the 10 upper portion of the body of the valve extends through the same. To connect the valve with the arm the annular enlargement of the arm is provided with bayonet slots 19 to receive the opposite ends of a pin 20 extending through and rigidly secured to the body of the valve. The inner end of each horizontal portion of the slot is preferably provided with a shallow recess 21 to receive the adjacent end of the pin 20 which will be held in said recess by water pressure, thus preventing the accidental displacement of the valve.

The valve arm 16 is connected with a float and, in the present instance, the float is shown at 23 and is mounted on the end of an arm or lever 24 which is on a bracket 25 carried by the discharge spout 4 of the valve and which controls the operation of the valve. This lever is connected by means of a link 26 with the valve actuating arm in such a manner that the downward movement of the float will raise the valve actuating arm and the valve member, thereby opening the valve and permitting the entrance of the water into the tank. The valve member is usually provided at its lower end with a seat engaging portion of rubber, or other more or less yieldable material to cause a more perfect contact with the valve seat. The repeated contact of the valve with the valve seat causes a depression or indentation to be formed in this yieldable portion of the valve and thereby causes the valve to move downward a greater distance than it did when new. A very slight variation of the movement of the valve will cause a relatively large movement of the float about the end of the arm 24 and the variation of the movement of the valve will result in a marked variation in the amount of water which must enter the tank before the valve is closed by the action of the float. I have, therefore, provided means for adjusting the length of the float arm to compensate for this variation in the movement of the valve. To this end that portion of the arm 24 which is carried by the bracket 25 is formed separately from the body of the arm, as indicated at 34, and is provided with a slot arranged between the axis of the arm and the float and arranged at an inclination to the horizontal, as shown at 35.

The body of the arm 24 is provided with a laterally extending stud 36, which, in the present instance, is formed by bending the

end of the arm and which extends through the slot 35 and is provided with a thumb nut 37. The portion 34 of the arm 24 is provided with a guide portion 38 which may be formed by bending the end of the part 34 of the arm at right angles to the body thereof and providing the same with an aperture to receive the arm 24, thus holding the arm against movement about the axis of the stud 36. This construction enables the 75 arm to be adjusted to compensate for the variations in the movement of the valve. It will be noted that the body of the valve member fits loosely within the annular portion 18 of the arm 16, thereby permitting a slight 80 lateral displacement of this annular portion of the arm due to its pivotal mounting. I also prefer to provide means to prevent the displacement of the valve member during the filling operation. To this end I have 85 provided the body of the valve member with a longitudinal slot 27 arranged in the upper portion thereof and have formed the arm 16 with a spur 28 extending in front of this slot and adapted to be moved into the slot 90 when the arm is moved upward to open the valves. Thus, the valve member is held against rotatory movement and any vibration to which it may be subjected by the passage of the water will not disconnect it from 95 the arm.

Valves of this type are commonly provided with what is known as a refilling pipe, 29, which is connected with the valve casing or discharge spout. In repairing the 100 valve, or for other reasons, it is sometimes necessary to disconnect this refilling pipe and I have, therefore, provided a special form of connection which will facilitate the connecting and disconnecting of the pipe, 105 and further, have provided means for regulating the flow of water through this refilling pipe. To this end I have provided the refilling pipe 29 with an elbow which is screwed into the spout 4, and have mounted 110 a valve 33 in the spout to control the flow of water through the refilling pipe.

While I have shown and described one embodiment of the invention it will be understood that this has been chosen for the 115 purposes of illustration only, and that I do not desire to be limited to the details of construction shown and described, for obvious modifications will occur to a person skilled in the art. And further, I wish it to be understood that while the invention is designed primarily for use in connection with float valves many of the features thereof are applicable to valves which are operated or controlled by means other than floats.

Having thus fully described my invention, what I claim as new and desire to secure by Letters Patent, is:—

1. In a valve, a casing comprising a chamber having an inlet and an outlet and pro-

vided with a valve seat, said casing also having a guide opening in alinement with said valve seat, a valve member slidably mounted in said opening for movement into and out of engagement with said valve seat and removable from said guide opening, and an actuating arm mounted adjacent to the casing but out of alinement with said guide opening, said arm and said valve member having interlocking parts arranged for movement into and out of engagement by the rotation of said valve member, said arm and said valve member also having means to prevent the accidental disengagement of said interlocking parts.

2. In a valve, a casing comprising a chamber having an inlet and an outlet and provided with a valve seat, said casing also having a guide opening in alinement with said valve seat, a valve member slidably mounted in said opening for movement into and out of engagement with said valve seat and removable from said guide opening, an actuating arm mounted adjacent to said casing but out of alinement with said guide opening, said arm and said valve member having interlocking parts arranged for movement into and out of engagement by the rotation of said valve member, said arm and said valve member also having parts arranged to be brought into coöperative relation when said valve member is moved to its open position, to prevent the disengagement of said interlocking parts.

3. In a valve, a casing comprising a chamber having an inlet and an outlet and provided with a valve seat, said casing also having a guide opening in alinement with said valve seat, a valve member slidably mounted in said opening for movement into and out of engagement with said valve seat and removable from said guide opening, and an actuating arm mounted adjacent to the casing and out of alinement with said guide opening, said arm and said valve member having interlocking parts arranged for movement into and out of engagement by the rotation of said valve member, said valve member having a recess and said arm having a part arranged to enter said recess when said arm is moved in a direction to open said valve.

4. In a valve, a casing comprising a chamber having an inlet and an outlet and provided with a valve seat, said casing also having a guide opening in alinement with said valve seat, a valve member slidably mounted in said opening for movement into and out of said engagement with said valve seat and removable from said guide opening, and an actuating arm mounted adjacent to said casing, but out of alinement with said guide opening, said arm and said valve member having interlocking parts controlled by the rotation of said valve member and also hav-

ing means to normally resist the rotation of said valve member when it is in either its open or its closed position.

5. In a valve, a casing comprising a chamber having an inlet and an outlet and provided with a valve seat, said casing also having a guide opening in alinement with said valve seat, a valve member slidably mounted in said opening for movement into and out of engagement with said valve seat and removable from said guide opening, said valve member having a part extending beyond the end of said valve casing, an actuating arm movably mounted adjacent to said casing, extending transversely to said valve member and having an annular portion adapted to receive said valve member, said annular portion being of a diameter greater than the greatest diameter of said valve member, whereby said valve member can be withdrawn from said guide opening through the annular portion of said arm, said annular portion of said arm having a bayonet slot and said valve member having a pin adapted to enter said slot, a part carried by said arm and adapted to be moved into engagement with said valve member to hold the same against rotatory movement and thus prevent the separation of said valve and said arm.

6. In a valve, a casing comprising a chamber having an inlet and an outlet and provided with a valve seat, said casing also having a guide opening in alinement with said valve seat, a valve member slidably mounted in said opening for movement into and out of engagement with said valve seat and removable from said guide opening, said valve member having a part extending beyond the end of said valve casing, an actuating arm movably mounted adjacent to said casing, extending transversely to said valve member and having an annular portion adapted to receive said valve member, said annular portion being of a diameter greater than the greatest diameter of said valve member, whereby said valve member can be withdrawn from said guide opening through the annular portion of said arm, said annular portion of said arm having a bayonet slot and said valve member having a pin adapted to enter said slot, said valve member having a slot, a spur secured to said arm and arranged to be moved into and out of said slot by the movement of said arm.

7. In a valve, a casing comprising a chamber having an inlet and an outlet and provided with a valve seat, said casing also having a guide opening in alinement with said valve seat, a valve member slidably mounted in said opening for movement into and out of engagement with said valve seat and removable from said guide opening and extending beyond the end of said casing, an actuating arm movably mounted near the

end of said casing and having a part extending about said valve member and arranged out of the path of said valve member when the same is withdrawn from said casing, said 5 part of said arm having a bayonet slot, a pin carried by said valve member to enter said slot, a part carried by said arm and adapted to engage said valve member to hold the same against rotation when said arm is 10 moved in one direction.

8. In a valve, a hollow casing having a partition dividing the same into two chambers, said partition being provided with a 15 guide opening, one of said chambers having an inlet and an outlet and also having a valve seat arranged in alignment with the opening in said partition, the other of said chambers having a relief port, and also having a guide opening arranged in alignment 20 with the opening in said partition, a valve member slidably mounted in said casing for movement into and out of engagement with said valve seat and having enlarged portions fitting within the respective guide openings, 25 said enlarged portions being of such a size and so arranged that the longitudinal movement of said valve will carry the ends of said enlarged portions past the respective edges of said openings, and an actuating device to impart movement to said valve member.

9. In a valve, a hollow casing having a partition dividing the same into two chambers, said partition being provided with a 35 guide opening, one of said chambers having an inlet and an outlet and also having a valve seat arranged in alignment with the opening in said partition, the other of said chambers having a relief port, and also having a guide opening arranged in alignment 40 with the opening in said partition, a valve member slidably mounted in said casing for movement into and out of engagement with said valve seat and having enlarged portions fitting within the respective guide openings, 45 said enlarged portions being of such a size and so arranged that the longitudinal movement of said valve will carry the ends of said enlarged portions past the respective edges of said openings, said valve member 50 also having a part extending beyond the end of said valve casing, an actuating arm pivotally mounted on said casing, extending transversely to said valve member and having a portion extending about the projecting

end of said valve member and arranged out of alignment with said guide opening, whereby said valve member can be withdrawn from said opening, said arm and said valve member having interlocking parts to operatively connect them one to the other.

10. In a valve, a casing comprising a chamber having an inlet and an outlet and provided with a valve seat, said casing also having a guide opening in alignment with 65 said valve seat, a valve member slidably mounted in said opening for movement into and out of engagement with said valve seat, and removable from said guide opening, an actuating arm mounted adjacent to the casing but out of alignment with said guide opening, said arm and said valve member having cooperating parts to connect them together, a second arm operatively connected with said actuating arm, said second arm 70 comprising two parts, one of said parts being pivotally mounted on a fixed support and connected with said actuating arm and also having an inclined longitudinal slot, the other part of said arm being slidably 75 mounted for longitudinal movement on the first mentioned part thereof and having a lateral projection extending through said slot, and means for securing said projection in adjusted positions in said slot.

11. In a valve, a casing comprising a chamber having an inlet and an outlet and provided with a valve seat, said casing having a guide opening in alignment with said valve seat, a valve member slidably mounted in said opening for movement into and out of engagement with said valve seat, a controlling arm mounted adjacent to said casing and comprising two parts, one of said parts being pivotally mounted on a fixed support connected at one end with said valve and having an inclined slot, the second part of said arm being slidably mounted on the first part of said arm for bodily movement longitudinally thereof and having a projection extending through said slot and means for securing said projection in adjusted positions in said slot.

In testimony whereof, I affix my signature in presence of two witnesses.

JOSEPH McCARTHY.
